DESIGN FOR A SURGICAL LAMP

John T. Armbruster, Niagara Falls, N. Y., assignor to American Optical Company, Southbridge, Mass., a voluntary association of Massachusetts

Application May 11, 1946, Serial No. 129,594

Term of patent 14 years

(Cl. D48—24)

To all whom it may concern:

Be it known that I, John T. Armbruster, a citizen of United States of America, residing at 237 74th Street, Niagara Falls, in the county of Niagara and State of New York, have invented a new, original and ornamental Design for a Surgical Lamp, of which the following is a specification, reference being made to the accompanying drawings, forming a part thereof.

Fig. 1 is a perspective view of a surgical lamp embodying the new design;

Fig. 2 is a top plan view of the surgical lamp, shown in Fig. 1; and

Fig. 3 is a rear elevational view thereof.

The characteristic features of the design reside in the portions shown in full lines in the drawings.

I claim:

The ornamental design for a surgical lamp, substantially as shown and described.

JOHN T. ARMBRUSTER.
